UNITED STATES PATENT OFFICE.

JOHN PRESTON PARK, OF BELOIT, KANSAS.

LIFE-SAVING SUIT.

1,081,862.

Specification of Letters Patent. Patented Dec. 16, 1913.

Application filed April 26, 1913. Serial No. 763,773.

To all whom it may concern:

Be it known that I, JOHN P. PARK, a citizen of the United States, and a resident of Beloit, in the county of Mitchell and State 5 of Kansas, have invented a new and Improved Life-Saving Suit, of which the following is a full, clear, and exact description.

My invention relates to a suit more particularly designed to be worn by marine 10 travelers in case of shipwreck.

The suit is made from waterproof material, and may be provided with a life preserver, or be adapted to receive an ordinary life preserver.

15 The invention will be particularly explained in the specific description following.

Reference is to be had to the accompanying drawings forming a part of this specification, in which similar characters of reference indicate corresponding parts in all the views.

Figure 1 is a perspective view showing my improved suit in position on a wearer; Fig. 2 is an enlarged cross sectional view 25 of the body portion of the suit; Fig. 3 is an enlarged vertical sectional view of the hood; Fig. 4 is a developed view of the hood; Fig. 5 is a fragmentary face view of the closing strips for the opening of the 30 body, the fasteners for the strips being omitted; Fig. 6 is a cross sectional view of the elements shown in Fig. 5; Fig. 7 is a fragmentary face view showing the fastening means for the strip; Fig. 8 is a cross sectional view of the elements shown in Fig. 7; and Fig. 9 is a fragmentary perspective 35 view of a slightly modified form of fastener to be employed at the upper end of the body.

In forming a suit in accordance with my 40 invention, a body 10 is formed of suitable waterproof material, and is provided with legs and arms, the arms, if desired, having integral mitts 10^a. The body may have applied thereto a pneumatic life preserver 11, 45 which may be inflated through the medium of a tube 12 to be fitted with the usual valve (not shown).

The body of the garment is formed with an opening at the front, applied to the edges 50 of which opening are strips 13, secured at their lower ends to a bowed spring 14 by

rivets 14^a or other suitable means. The opposed edges of the strips 13 are given a tongue and groove formation, as indicated at 15, and it is to be understood that in practice, the strips may be formed of any suitable flexible material, preferably of rubber, having sufficient body and yet possessing the desired resiliency to permit the strips to conform to the contour of the body of the 55 wearer and permit of movement of the body. As shown in Figs. 5 and 6, a rubber packing strip 14^b may be employed between spring 14 and the ends of the strips 13, and have a tongue and groove engagement with said 60 strips as at 14^c.

In order to provide efficient fastening means for the strips 13 to effect a tight closure of the front opening, mating fastener elements 16, 17, are secured respectively to the strips, the one element 17 having a T-head 18 beneath which forwardly projecting forked members 19 on the element 16 may engage, there being a flange or stop 20 on the element 16 at the base of 75 the forked members 19 to come to a bearing against the T-head 18 when the fasteners are brought together in engagement. There is carried also by one strip, as 17, a hasp link 21 hinged as at 22, and adapted to be 80 passed over a bent locking lever 23 pivoted at one end as at 24, to the opposite strip 13, the lever having between its free end and fulcrum, an inturned hook 23^a to engage the cross bar 21^a at the free end of the hasp link, 85 the arrangement being such that the lever may be swung inward across its center of movement to hold the link in fastened position, the movement of the lever serving to tightly press the opposed edges of the strips 90 13 with their tongue and groove connection together, to exclude water. The fastener elements 16 and their mating members 13 are arranged in pairs, the pairs being preferably integral, and between the elements of 95 each pair the described links 20 and levers 23 are arranged.

There may be further employed in connection with the link and lever and the fastening elements 16, 17, thumb screws 25 100 adapted to pass through both strips and both fastening elements, so that upon the tight-

ening of the thumb screws a leverage will be exerted to further tightly clamp the strips since the screws engage the fastening elements between the said strips and the point of engagement between the said elements. For the major portion of the length of the strips 13, the fastener elements 16, 17, arch toward each other, but those fastening elements 16^a, 17^a, at the upper ends of the strips, and therefore directly beneath the chin, have less projection to prevent possible discomfort, said elements extending over the faces of the strips in substantially flat form, as best seen in Fig. 9. The modified fasteners are however, provided with elements 18^a, 19^a, 20^a, corresponding with similar elements in Figs. 7 and 8.

The body is provided with a hood 26, and in order that the edge portions of the hood 20 may be closed against the head of the wearer sufficiently tight to exclude water without affording discomfort, the hood at the opening at the front is faced with strips 27 preferably of sheepskin having fleece 25 thereon, said strips extending in opposite directions from the throat upwardly around the hood, and having opposed diagonal edges as at 27^a. The fastening strips pass loosely through guide loops on the hood, and the 30 connection between the hood and the smaller end of each strip is by means of an elastic connecting strip 29, so that tension in opposite directions will be exerted on the strips to hold them snugly against the head of the 35 wearer. In practice, the fleece may have applied thereto a heavy oil, vaseline, or the like, to assist in excluding the water. The hood at the top may have elastic gore members 30, 31, as indicated in Fig. 4, to assist 40 in giving the hood a close fit.

The hood may be provided with a mask 32, to guard against spray, the guard being sustained by arms 33 pivoted as at 34, to the hood and having a window 35 of celluloid, mica or the like.

Having thus described my invention, I claim as new, and desire to secure by Letters Patent:

1. A life saving suit having an opening in 50 the body thereof, provided with flexible strips at the edges of the opening, fastening means comprising mating fastener elements carried respectively by the strips, one element having a T-head and the other element having forked members adapted to engage beneath the said head, and clamps to draw the strips and fasteners toward each other.

2. A life saving suit having an opening in 60 the body thereof, provided with strips ranging along the edges of the opening, mating fastener elements carried respectively by the

strips, and a clamp arranged in connection with said fastener elements to draw the same and the strips toward each other. 65

3. The herein-described garment having an opening in the body thereof, provided with strips at the edges of said opening, fastening means consisting of pairs of mating elements spaced apart, and clamps carried by the respective strips and disposed between the fastening members of a pair. 70

4. The herein-described garment having an opening, and flexible strips along the edges of the opening, said strips having respectively a tongue and groove at the opposed edges and mounted to move toward and from each other, and fastening means for holding the strips in closed position. 75

5. The herein-described garment having 80 an opening therein, strips formed of resilient material and mounted to open and close, a link on one strip, and a lever on the other strip adapted by engagement with said link to press the resilient strips into close engagement. 85

6. The herein-described garment having an opening therein, strips ranging along said opening and mounted to open and close, fastening members carried respectively by said 90 strips, and clamp screws engaging said fastening members to draw the same, and with them, the strips, into close engagement.

7. A life saving suit, having a waterproof body, and a waterproof hood open at the 95 front, the hood having around the front thereof facing strips adapted to move relatively to each other to contract or enlarge the opening.

8. A hood having an open front, and facing strips at said front movable relatively to each other around the opening, for the contraction and enlargement of the hood. 100

9. The herein-described hood having an open front, guide loops at the front, and facing strips extending around the opening through said loops, the facing strips being movable in the loops in opposite directions. 105

10. A hood having an open front, and facing strips extending around the hood at the 110 front, said strips having opposed diagonal edges.

11. In a life saving suit, a hood open at the front, and having facing strips extending around the hood at the opening, the said strips being movable relatively to each other in opposite directions to contract or enlarge the opening, and each having an elastic connection at one end with the hood. 115

12. In a suit of the character described, 120 a body having a hood formed with an opening at the front and with an elastic gore at said opening, and facing strips extending around the hood and movable relatively.

with each other to contract or enlarge the opening, the said strips each having an elastic connection at one end with the hood.

13. A garment having an opening provided with co-acting fastener members, one member having a T-head, and the other having arms adapted to engage transversely beneath the said head.

In testimony whereof I have signed my name to this specification in the presence of 10 two subscribing witnesses.
